UNITED STATES PATENT OFFICE

FERDINAND REICHEL, OF NEW HAVEN, CONNECTICUT, ASSIGNOR TO NATIONAL FOLDING BOX COMPANY, OF NEW HAVEN, CONNECTICUT, A CORPORATION OF NEW JERSEY

DISPENSING CARTON

Application filed September 22, 1928. Serial No. 307,708.

The invention relates in general to containers, and more particularly to a paper board package which lends itself for dispensing the packed material conveniently.

5 According to one form of the invention a container is made from paper board suitably creased and scored to form a rectangular box for enclosing a sterile article such as medical gauze, which must be kept sterile during use. 10 The container is provided with a detachable top wall which is folded away from the body of the container for admission of the roll of gauze or other sterile article during packing. The container is then closed and the 15 gauze placed on the market in a safe and sanitary condition. When it is desired to dispense the gauze, the container is partially opened, sufficiently to pull out the gauze, the container remaining substantially closed during this time, thereby protecting the body of the gauze and keeping it sterile. After the 20 desired amount of gauze has been dispensed, it is cut off and the box again closed.

The invention also consists in certain new 25 and original features of construction and combinations of parts hereinafter set forth and claimed.

Although the novel features which are believed to be characteristic of this invention 30 will be particularly pointed out in the claims appended hereto, the invention itself, as to its objects and advantages, the mode of its operation and the manner of its organization may be better understood by referring to the 35 following description taken in connection with the accompanying drawings forming a part thereof, in which

Fig. 1 is a perspective of the container partially open with the contained gauze in 40 position for dispensing;

Fig. 2 is a development of the blank from which the container is made, the dot and dash lines representing creases;

Fig. 3 is a perspective showing the container in partially assembled condition;

Fig. 4 illustrates the container assembled and ready for the bodily insertion of the article to be packed; and

Fig. 5 is a section on the line 5—5 of Fig. 1 illustrating the manner of closing the container.

In the following description and in the claims part will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinafter defined and claimed.

Referring now to the drawings, the container is made from a blank suitably cut and scored as shown in Fig. 2, the solid lines denoting cuts and the dot and dash lines denoting scores. The container is assembled by bending the parts along the scored or weakened lines, to form the container illustrated in the other figures.

The container comprises a bottom wall 10 to which is suitably secured a back wall 11 and a front wall 12. The back wall has secured thereto a top wall or main cover 13 to 15 which is secured a front flap or auxiliary cover 14 having a front tongue 15. The front wall has secured thereto at the upper edge thereof an inner liner wall 16. The front wall has outer side flaps 17 secured thereto, each flap having a cut away portion 18 forming a tongue 19. The back wall 11 is provided with inner side flaps 20 having slots 21 therein and each having secured thereto a bottom flap 22. The top wall has side cover 25

flaps 23 secured thereto, each side cover flap having a bottom tongue 24.

To assemble the container the back and front walls 11 and 12 are bent upwardly and the inner side flaps 20 are bent to form the end walls, the bottom flaps 22 overlying the bottom 10. The front lining 16 is doubled over on the front wall 12 and the walls 12 and 16 bent upwardly to the position shown 10 in Fig. 4, the outer side flap 17 being bent over the inner side flaps 20 and the tongues 19 inserted in the slits 21.

In this position the box is ready to receive the roll of gauze 30 and, after it has been inserted, 15 the top wall 13 is folded down with the front flap 14 overlying the front wall and the side cover flaps 23 overlying the end walls, and the tongue 15 is inserted in the slot 25 in the front wall 12 and bottom 20 tongues 24 inserted between the bottom wall 10 and the bottom flaps 22, as illustrated in Fig. 5. The end of the gauze roll 30 may be sealed under flap 14 to provide easy access thereto when the package is opened.

25 In this position the box is tightly sealed and the gauze or other article effectively protected from contamination. When it is desired to use the gauze or other article, the front flap 14 and front tongue 15 are removed 30 exposing the end of the gauze. The gauze can then be pulled out to the desired extent through the slot formed between the front wall 12 and the top wall 13 and, after the desired amount has been dispensed, the front 35 tongue 15 is re-inserted in the slot 25.

Thus it will be seen that a container has been provided which is made from sheet paper board which can be made comparatively inexpensively. It can be shipped flat to 40 the consumer thereby taking up small cargo space and is so shaped that there is a minimum of waste in cutting the blanks. The gauze may be packed tightly and thoroughly 45 protected in this package, which is adequately strong, and then may be conveniently dispensed in the manner explained above. The gauze is not only effectively packed during shipment but is also protected during use, thereby insuring sterile gauze until it is completely used.

While certain novel features of the invention have been shown and described and are pointed out in the annexed claims, it will be understood that various omissions, substitutions and changes in the forms and details of the device illustrated and in its operation 55 may be made by those skilled in the art without departing from the spirit of the invention.

60 What is claimed is:

1. A dispensing carton made up of a blank comprising a bottom wall, a front wall having a slit and a back wall secured to said bottom wall, a top wall secured to the upper 65 edge of said back wall, a front tongue secured

to said top wall, first side flaps secured to said front wall, second side flaps secured to said back wall and overlapping said first side flaps, bottom flaps secured to one pair of said side flaps, side cover flaps secured to said top wall, bottom tongues secured to said side cover flaps, said bottom flaps resting on said bottom wall, said side cover flaps disposed over said side flaps and said bottom tongues tucked between said bottom flaps and bottom wall, 70 said front tongue being tucked in said slit in said front wall.

2. A dispensing carton made up of a blank comprising a bottom wall, a front wall having a slit and a back wall secured to said bottom wall, an inner front lining wall secured to the upper edge of said front wall, a top wall secured to the upper edge of said back wall, a front flap secured to said top wall, a front tongue secured to said front flap, outer side flaps secured to said front wall, 75 said outer side flaps being notched to form connecting tongues, inner side flaps secured to said back wall and having slits in which said connecting tongues are disposed, bottom flaps secured to said inner side flaps, side cover flaps secured to said top wall, bottom tongues secured to said side cover flaps, said bottom tongues resting on said bottom wall, 80 said side cover flaps disposed over said side inner and outer flaps and said bottom tongues tucked between said bottom flaps and bottom wall, said front tongue being tucked in said slit in said front wall.

3. A sanitary dispensing container comprising a receptacle having a main cover, an auxiliary cover connected to and arranged to be opened independently of said main cover, means for retaining said main cover in its closed position and separate means for retaining said auxiliary cover in its closing position.

4. A sanitary dispensing container comprising a receptacle having a main cover, an auxiliary cover connected to and arranged to be opened independently of said main cover and means comprising flaps extending from said main cover overlying opposite walls of said receptacle and having tuck-in ends for retaining said main cover in its closed position.

5. A sanitary dispensing container comprising a receptacle having a main cover, an auxiliary cover arranged to be opened independently of said main cover to partially open the container, means comprising flaps extending from said main cover overlying opposite walls of said receptacle, said flaps having tuck-in ends for retaining said cover in its closed position and said auxiliary cover having a tongue arranged to be secured to the front wall of the receptacle whereby said auxiliary cover is retained in its closed position.

6. A sanitary dispensing container of the

class described comprising a receptacle, a main cover for said receptacle, means for retaining said cover in its closed position, an auxiliary cover connected with said main cover and adapted to be opened independently of said main cover whereby contents of the receptacle may be dispensed through an orifice uncovered by the opening of said auxiliary cover.

10 In testimony whereof I have hereunto set
my hand.

FERDINAND REICHEL.
